UNITED STATES PATENT OFFICE

WALTER S. LANG, OF KENDALLVILLE, INDIANA, ASSIGNOR TO THE LANG ELECTRIC MFG. COMPANY, OF KENDALLVILLE, INDIANA, A CORPORATION OF INDIANA

ELECTRIC WATER HEATER

Application filed June 4, 1928. Serial No. 282,698.

This invention relates to improvements in water heaters, and it consists of the constructions, combinations and arrangements herein described and claimed.

5 An object of the invention is to provide a water heater having a heating unit in which a heating element is made to follow a water pipe, so that the latter will be subjected to a continuous line of heat.

10 Another object of the invention is to provide an electric or gas water heater having a heating unit comprising a copper or other pipe coil and a helical electrical or gas heating element interposed between the convolutions of the coil so that the latter are subjected directly to a continuous line of heat from the former when active.

15 A further object of the invention is to provide a novel construction in the heating unit, permitting removal thereof for repairs from the so-called inside tank or heating chamber without the need of emptying the main water tank.

20 Other objects and advantages will appear in the following specification, reference being had to the accompanying drawings, in which

Figure 1 is a perspective view of the improved water heater,

25 Figure 2 is a central vertical section thereof,

Figure 3 is a detail section of the upper end of the heating unit,

30 Figure 4 is a detail section of the lower end of the heating unit,

Figure 5 is a detail vertical section particularly illustrating the electrical terminals of the electrical resistance or heating element,

35 Figure 6 is a cross section taken on the line 6-6 of Figure 3,

Figure 7 is a detail perspective view of one of the refractors or insulating segments,

40 Figure 8 is a longitudinal section of the thermostat used in connection with the heater,

45 Figure 9 is a detail vertical section illustrating the adaptation of a gas helix as the heating element,

Figure 10 is a detail sectional view of the gas helix.

50 Although the convenience of hot water and

the need therefor is felt in every household there are still many of the latter which are not equipped with a modern and efficient water heating apparatus. While it is true that some residences are equipped with automatic hot water heaters yet it is equally true that the persons in the majority of homes must either content themselves with the pleasure and convenience of hot water only during the winter months when a furnace fire is maintained, or delegate someone to light the gas water heater when hot water is wanted in the summer.

55 Inasmuch as the original cost and the subsequent cost of maintenance of known automatic water heaters is usually high, it is one of the purposes of the invention to provide a construction which will permit the marketing thereof at a moderate cost, and also one in which the cost of electrical current will be low because of the mode in which the heat is applied. In other words, the heat is applied directly and continuously to the heating coil, so that all of it will be utilized.

60 By way of further preface it is stated that while the automatic heater is primarily electrical in nature it is also proposed to employ gas as the heating medium. The common principle is that of the interposition of an electrical resistance or gas helix between the convolutions of a heating coil, so that the heat is applied directly and continuously to the heating coil, so that all of it will be utilized.

65 By way of further preface it is stated that while the automatic heater is primarily electrical in nature it is also proposed to employ gas as the heating medium. The common principle is that of the interposition of an electrical resistance or gas helix between the convolutions of a heating coil, so that the heat is applied directly and continuously to the heating coil, so that all of it will be utilized.

70 Reference is made to the drawings. An insulating jacket 1 contains and protects a main water tank 2, from which it is spaced on all sides, excepting the bottom, thus to insulate the water tank by the volume of surrounding air. A cover 3, of a removable nature provides for access to the jacket upon occasion.

75 Situated within the main water tank is a so-called inside tank or heating chamber 4 which contains the heating unit seen in Figures 3, 4 or 9. The tank 2 obviously is intended to contain water which is introduced at a cold water inlet 5 and discharged at a hot water outlet 6. The heating unit is interposed between the two pipes so that the water will be heated to a high temperature on its passage from the inlet to the outlet when the unit is in action.

The bottom 7 is common to the jacket 1 and main tank 2. The heating chamber 4 is fitted around the rim of an opening 8 in the bottom. Access is thus had to the inside of the heating chamber. As can be understood 5 already, the entire heating unit may be withdrawn from the heating chamber 4 without emptying the main tank 2. This is a feature of great convenience should repairs or replacements become necessary.

10 The heating unit comprises a copper or other water pipe 9 shaped into a coil so that a large area may be available as a heating surface. A heating element, either in the form of an electrical resistance wire 10 (Figs. 3 and 15 4) or a helical gas burner 11 (Figs. 9 and 10), is disposed between the convolutions of the coil from one end to the other, so that the heat from either element may be applied to the coil in a continuous line. A relatively 20 large coil area is directly affected by the heating element so that the water will be quickly raised to a high temperature.

Porcelain or other suitable insulating segments 12 are assembled between the convolutions of the coil 9 to carry the resistance wire 10. The segments have grooves 13 (Fig. 7), collectively forming a substantially continuous spiral groove when the segments are fitted 30 end to end, into which the resistance wire is laid. The groove is sufficiently deep that the resistance wire when laying on the bottom cannot touch the copper coil immediately thereabove and cause a short circuit.

35 The resistance element is retained in the groove in spaced relationship from the coil immediately above by lugs 14 (Fig. 7). These lugs are formed on opposite edges of the groove and oppose depressions 15 on the confronting side of the groove. The depressions make room for pressing the resistance wire into place in the spiral groove when assembling the heating unit. The top of the resistance wire comes slightly below the bottoms of the lugs, thus indicating a sufficient 40 clearance between the top of the resistance element and the bottom of the coil immediately above to safely clear the latter.

A close nesting of the insulating segments 50 between the convolutions of the coil 9 is obtained by forming concavities 16 in the bottom of the segments. These concavities receive the upper part of the coil immediately beneath. Transverse grooves 17 in the bottoms of the segments 12 admit screws 18 by which the segments are affixed to the upright bars 19 of an internal cage.

This cage includes and is closed by top and bottom plates 20 and 21, four sides of 60 each of which are flattened as shown in Figure 6 to permit screwing the bars in place as at 22. The cage slips inside of the water coil 9 and has a tight fit therein. The resistance element is inserted in the grooves 65 of the segments 12 as the latter are fitted

between the convolutions of the coil, and as the segments are secured to the cage the resulting heating assembly constitutes a unit in which the component parts are absolutely tight. The assembly may be inserted into and removed from the heating chamber 4 as a unit as will presently appear. 70

Copper rods 23 (Fig. 5) form parts of the terminals of the electrical resistance coil 10. The ends of the rods are threaded at 75 24 and 25 respectively to screw into insulating bushings 26 at the top, and have binding posts 27 screwed thereupon at the bottom. Smooth portions of the rods pass through bottom insulating bushings 28, and according to the arrangement shown in Figure 5, the screwing up of the binding posts 27 will lock the rods and insulators in position upon the internal cage. The upper and lower ends of the resistance wire 10 are 80 suitably secured to the respective rods as indicated at 29 and 30.

The electrical system of the heater includes the thermostat in Figure 8. The fixed and movable contacts 31 and 32 control an electrical circuit 33 which embraces the resistance wire 10 and includes a manual switch 34 by which the current is turned on and off when desired. The thermostat automatically controls the operation of the heating unit when the switch 34 is turned on. 95

An ebonite rod 35 (Fig. 8) is encased by a copper or other suitable tube 36 which is projected into the main water tank 2 so that the changes in temperature of the water may affect the ebonite rod. The inner end of the latter is rigidly secured at 37 to a washer or other plug 38 that seals the corresponding end of the tube. The left or outer end of the tube is received by and welded at 39 in one end of a brass or other nipple 40. The ends of the nipple are threaded to respectively screw into a brass mounting plate 41 and into a bushing 42. The latter is screwed into the tank 2, and is suitably packed so that there may be no leakage of water into the insulating space between the jacket and tank. 100

A centering washer 43 has a hole 44 to receive the free and otherwise unsupported left end of the ebonite rod 35. That end carries a contact screw 45 which may be set at various adjustments by a jam nut 46. The screw 45 co-acts with a similar contact screw 47 on a movable fibre bar 48. This bar carries the electrical contact 32, the complementary contact being carried by a fibre bar 49 fixed upon the mounting plate 41 as at 115 50. A hinge block 51 carries the movable bar 48. 120

It is to be noted in Figure 8 that the inside diameter of the tube 36 is greater than the diameter of the ebonite rod, thus making it necessary to provide the washer 43 in order to keep the ebonite rod in line, and also keep 125

the contact screws 45 and 47 in line. The weld at 39 prevents any leakage of water around the tube 36.

The principle involved in the operation of the thermostat is that ebonite has a very high coefficient of expansion, and since the ebonite rod is held rigid at the right end of the copper tube, and although the copper tube does expand slightly, the far greater 10 expansibility of the ebonite rod makes the expansion of the tube negligible so that the desired operation results.

Any expansion of the ebonite rod will be toward the left, or in the direction of its freedom. When the heads of the contact screws 15 45 and 47 meet, any continuing expansion of the ebonite rod will separate the electrical contacts 31 and 32 and so automatically open the electric circuit. Reduction in the temperature of water will have the reverse effect 20 upon the thermostat. The contraction of the rod 35 will permit the contacts 31 and 32 to re-engage so that the resistance element 10 is heated again.

25 Reverting to the structure of the water heater, the bottom and inlet end of the coil 9 is fitted with a union 52 and a T 53 by which immediate connection is made with the bottom 7 of the water tank 2. The upper or 30 outlet end of the coil has an elbow 54 (Figs. 2 and 6) into which an outlet pipe 55 is screwed. This pipe is connected through the medium of a union 56 with the hot water outlet 6. The hot water outlet communicates 35 both with the tank 2 and with the pipe 55.

A casing 57 encloses the exposed lower end of the heating unit. This casing is readily removable so that the heating unit may be gotten at. The heating unit is easily removed 40 by simply unscrewing the unions 52 and 56 then removing either the nipple at the right of the union 56 or both the nipple and the adjoining elbow, whereupon the outlet pipe 55 will pass through the tube 58 when the unit is 45 withdrawn from the bottom of the chamber 4. A tube 58 surrounds the outlet pipe 55 and closes off the tank 2. In Figure 9 this tube 58 will serve the purpose of a flue through which the products of combustion of the gas burner 11 may escape. It may be said in connection 50 with Figure 9 that the helical gas burner 11 occupies the spaces between the convolutions of the coil 9 so that the heat from the gas jets may be continuously applied throughout the 55 entire length of the coil. The mixing valve 59 of the gas burner will be housed by the casing 57, and the usual gas cock 60 will be located on the outside. A suitable thermostat 61 may be used in both forms of the invention.

The operation

is readily understood. It is observed in Figure 2 that the hot water outlet 6 has communication both with the main water tank 2 and

the outlet pipe 55 of the heating unit, the latter being established through the branch pipe that carries the union 56. Provision is thus made for a local circulation of water as well as for the flow and instantaneous heating of the water as when a faucet is opened.

The local circulation will occur as long as the heating unit is in operation, in other words, as long as the electrical contacts 31 and 32 are in engagement and close the circuit through the heating element 10. Hot water will flow out of the pipe 55 into the top of the tank 2, while cooler water will enter the bottom inlet of the coil 9 for the heating process. As soon as the temperature of the water becomes such that the ebonite rod 35 of the thermostat in Figure 8 is forced to expand a sufficient extent, the contacts 31 and 32 will become separated so that the electrical current is cut off for a time.

Figure 9 does not disclose an automatic control of the helical gas coil 11, but in practice any known automatic control may be employed. The principal purpose of the modification in Figure 9 is to show how gas may be employed as the heating medium of the coil 9 as well as electricity. In order that the principle of the heating unit may be common in both forms of the invention, the gas coil must follow the convolutions of the water coil 9 so that there may be a continuous line of heat against that coil from beginning to end.

One feature that has been emphasized is the removability of the heating unit whether that be adapted for electricity or gas. It is only necessary to undo a few connections when the entire unit may be abstracted from the heating chamber 4. By heating unit is meant the water coil 9 and the heating element 10 or 11. The ability to withdraw this unit for the making of repairs is a great convenience.

It is unnecessary to drain the water from the tank 2, or in fact disturb anything but the immediate connections to the heating unit. Most of the heat from the heating element will be transferred directly to the adjacent convolutions of the coil 9, but some of the radiant heat will warm the chamber 4 and tube 58, forming a hot core in the surrounding volume of water.

While the construction and operation of the improved water heater is that of a generally preferred form, obviously modifications and changes may be made without departing from the spirit of the invention or the scope of the claims.

I claim:

1. A water heater comprising a water tank, a heating unit comprising a water coil communicating at its extremities with the bottom and top of the tank, and a heating element situated between the convolutions of the coil and extending from one extremity to the

- other; and a heating chamber situated within the water tank, containing the heating unit and constituting a hot core for the volume of water in the tank.
5. 2. A water heater comprising a water tank, a heating unit comprising a coil having an inlet connected with one end of the tank, and an outlet pipe, and a heating element located between and following the convolutions of the coil from the inlet to the outlet; a heating chamber extending from one end of the tank and containing the heating unit, and a tube extending from the heating chamber to the opposite end of the tank encasing the pipe, said chamber and tube constituting a central hot core for a volume of water in the tank when the heating unit is in operation.
10. 3. A water heater comprising a water tank having a bottom with an opening, an inside tank located within the water tank having its walls fixed around the rim of the opening and having a tube extending to the top of the water tank, and a heating unit insertable into and removable from the inside tank through said opening, comprising a coil with a separable connection to one end of the water tank and an outlet pipe connected with the other end of the tank, situated in the tube and having a separable connection with the other end of the coil, and a heating element located between the convolutions of the coil.
15. 4. A water heater comprising a water tank with a cold water inlet and a hot water outlet, a heating chamber and tube situated within the tank between the ends, an outlet pipe contained by the tube being connected with the hot water outlet, and a heating unit contained by the heating chamber, being separably connected with said pipe and one end of the tank, and a heating element incorporated in said unit, being located between the convolutions of the coil to directly heat the latter, causing a local circulation of water in the absence of a flow from the hot water outlet, and instantaneous heating of the water in the coil when there is a flow from the outlet.
20. 5. In an electrical water heater, a heating chamber, and a heating unit capable of insertion into and abstraction from the heating chamber, comprising a coil, an electrical resistance following the convolutions of the coil, insulating means by which the resistance is carried, and a cage fitted up inside of the coil to which the insulating means is secured to complete the unit.
25. 6. In an electrical water heater, a heating chamber, and a separable heating unit located in the chamber comprising a coil, a cage fitted upon the coil, insulating means situated between the convolutions of the coil, acting as spacers and having a spiral groove, a resistance wire laid in the groove and serving to heat the convolutions of the coil immediately thereupon, and means securing said insulating means to the cage forming the unit.
7. In a water heater, a heating chamber, and a heating unit located in but separable from the chamber, comprising a coil, a cage fitted inside of the coil, a plurality of insulating segments having grooves collectively forming a spiral groove, and having concavities receiving the coil when located between the convolutions, a resistance wire of spiral formation laid in the groove, means retaining the wire in the groove and preventing contact with the coil, and means to secure the segments to the cage.
10. 8. In an electrical water heater, a heating chamber, and a heating unit comprising a coil, a cage fitted inside of the coil consisting of end plates and connecting bars, a plurality of insulating segments having grooves collectively forming a spiral groove and having transverse grooves, means extending through the transverse grooves into connection with the bars to secure said elements between the convolutions of the coil, a resistance wire of helical form laid in the groove and following the convolutions of the coil, and terminal connections for said resistance wire including rods spanning the end plates, bushings fitted in one of the plates in which one end of each rod is secured, bushings in the other plate through which the other ends of the rods extend, and binding posts carried by the latter ends.
15. 9. A water heater comprising a water tank with an internal heating chamber, a heating unit situated in said chamber comprising a coil, and an electrical resistance wire located between the convolutions of the coil, and means permitting the disassociation of the heating unit from the tank and heating chamber comprising a T and a union connecting one extremity of the coil with one end of the tank, and a pipe and a union connecting the other extremity of the coil with the other end of the tank.
20. 10. In an electrical heater, a heating chamber open at one end, a fluid coil, an electrical resistance following the convolutions of the coil, insulating means for said resistance, and means upon which the coil is mounted and to which the insulating means is attached composing a unitary heating element capable of insertion into and removal from the open end of the heating chamber as a unit.
25. 11. In an electrical heater, a heating chamber open at one end, a cage, a fluid coil having the convolutions disposed around the cage, and an electrical resistance having insulating means attached to the cage to space the convolutions.
30. 12. A water heater comprising a water tank, a chamber extending inside thereof but open to the outside at one end of the tank, a water coil and heating means therefor inserted in the chamber from the open end, and means by which immediate connection is made between one end of the coil and one end

of the tank constituting the support of one end of the coil and the heating means.

18. A water heater comprising a water tank having an inlet and an outlet, an encased heating unit contained by the water tank, comprising heating means and a water coil having its ends connected in communication with the water tank to cause a local circulation in the absence of a flow at said outlet.
